M. H. GABA,
PHONOGRAPH ILLUMINATING APPLIANCE,
APPLICATION FILED JAN. 27, 1919.

Patented Sept. 16, 1919.

FIG. 1.

M. H. GABA
INVENTOR.

BY R. J. McEntyre,
his ATTORNEY.

UNITED STATES PATENT OFFICE.

MELVIN H. GABA, OF PHILADELPHIA, PENNSYLVANIA.

PHONOGRAPH-ILLUMINATING APPLIANCE.

1,316,025.

Specification of Letters Patent. Patented Sept. 16, 1919.

Application filed January 27, 1919. Serial No. 273,261.

To all whom it may concern:

Be it known that I, MELVIN H. GABA, a citizen of the United States, residing at Philadelphia, in the State of Pennsylvania, have invented certain new and useful Improvements in Phonograph - Illuminating Appliances, of which the following is a specification.

This invention relates to improvements in illuminating appliances for phonographs for enabling the correct positioning of the records where the light is insufficient or the instrument is placed in a more or less darkened part of a room or is being operated during the twilight hour, before the lights are turned on.

The object of the invention is to provide a simple and efficient appliance for illuminating the record disks when the reproducer arm is being placed in the initial or starting position. The appliance comprises an electric circuit containing a battery, a lamp mounted on the upper portion of the horn, above the record disks, and a switch, the switch being attached to the handle or control lever to be conveniently pressed by the thumb to close the circuit when the handle or control lever is gripped in the act of positioning the reproducer arm as herein-after more fully described in connection with the accompanying drawings.

Referring in general terms to the said drawings, Figure 1 is a vertical sectional view of the upper portion of a phonograph cabinet showing my illuminating appliance applied thereto. Fig. 2 is a detail plan view of the handle or control lever, and the spring clip constituting the switch; and Fig. 3 is a cross section through the upper portion of the horn extension showing the lamp attaching devices thereon.

In a more particular description of the improvement the same reference characters are employed to denote similar parts in the drawings and description.

As is apparent from the drawings a simple form of concealed lamp circuit is shown consisting of a wire or conductor 1, which leads from one pole of a battery 2 and a wire or conductor 3 which leads from the other pole of said battery 2. The battery and conductors are concealed within the upper compartment 4 of the phonograph in which the horn 5 is housed. The other end of conductor 1 is secured at 6 to a conductor in the form of a resilient adjustable band 8 which is clamped at its overlapped ends around the upper portion 9 of the horn which lies above the record table 25. A lamp socket 10 is secured to said band 8 and receives a bulb or lamp 11 which lies adjacent to the record disks 12 and sufficiently above said disks to illuminate the records as placed in position and when the reproducer is being located. A band of insulation 13 fits around the horn extension 9 on the inside of the band or conductor 8 and as shown in Fig. 3 the ends of which also overlap and are clamped tightly to the horn extension 9 by an adjusting screw 14 which penetrates an oblong opening 15 in the outer end of the band 8, so that both bands 8 and 13 may be adjusted to horn extensions of different sizes. The insulation band 13 has an opening 16 therein through which the lamp socket contact point 17 makes contact with the horn which is a conductor of the electric current that supplies the lamp. The bands 8 and 13 are placed in position by removing the reproducer arm 18 and slipping said bands over the end of the horn extension 9 and adjusting them to the proper fit and then tightening the same. The terminal of conductor 3 connects with a switch consisting of a spring clip 19 which is mounted on the handle or control lever 20 and is insulated therefrom as shown in Fig. 2. The said handle or control lever 20 may be removed by unscrewing it and the said clip 19 may be easily placed over the rod from which said handle was removed and said handle or lever then replaced. It will be seen from Fig. 2 that the spring clip or switch 19 is on the side of the handle or control lever 20 in a convenient place to be pressed by the thumb of the hand gripping said handle to cause the contact point 21 thereof to make contact with contact point 22 which is on the reproducer mechanism manipulating rod 23. The lamp circuit is thus made through the horn when these contact points engage. The record is thus conveniently illuminated when the handle or control lever is in use by pressing the thumb against the spring clip 19. The bands 8 and 13 are extended outwardly as at 24 to provide for the usual tube on the horn for the electric stop. This stop feature is well

known to phonographs and constitutes no part of the present improvements and need be only incidentally mentioned.

Having described my invention, I claim—
5 In an illuminating appliance for Edison phonographs, the combination with the reproducer mechanism thereof, of an electric circuit, a lamp connected therein, an adjustable lamp support mounted on the horn
10 extension above the record table, and a switch the movable contact element of which is mounted on the control lever in a position

to be engaged by the hand to close the lamp circuit in manipulating the said control lever and the other contact element of which is 15 on the manipulating rod of the reproducer mechanism to which the said control lever is connected, whereby the lamp circuit is completed through the reproducer mechanism in positioning the records and is broken 20 when the hand releases the control lever.

In testimony whereof I affix my signature.

MELVIN H. GABA.
